UNITED STATES PATENT OFFICE

CHARLES HOFRICHTER, OF BRONSDORF, GERMANY

WAGON TILT

Application filed April 23, 1930. Serial No. 446,643.

The existing wagon tilts are only badly suited for use in connection with such freight goods as rough provender and the like, in that vegetables of this kind are so tightly enclosed in and by those tilts that they are exposed to the danger of becoming mouldy and also hot, perhaps in such a degree that the goods commence to burn. Besides, the existing tilts are likely to rot and to be torn when being placed upon, and taken off, the goods.

These and other drawbacks are obviated in and by my improved wagon tilt which allows of a thorough ventilation of the goods and can be pulled tightly down upon them without any danger of tearing, and besides, it can be used in a twofold manner, viz. not only as a wagon-tilt proper, but also as a tent or barrack or, more precisely, as a covering therefor, in which case at least two of these tilts are united with one another, as is also more fully described hereinafter. The thus improved tilt is illustrated diagrammatically and by way of example on the accompanying drawings on which Figure 1 is a bottom view of a tilt designed according to this invention; Figure 2 shows it in its position of use on a wagon with its freight; Figure 3 is a perspective view of two tilts put up and connected in such a manner as to form a tent or barrack.

The tilt consists of a longitudinal middle part *a* of strongest waterproof sail-cloth, raw silk, bast, or the like, and of two side parts *b b* which are united with said part by a comparatively large number of straps *c* which extend transversely to, and over, the parts *a* and *b* at the bottom surface thereof, and are sewn to, or otherwise connected with, them. At the ends of said straps are semicircular rings *r* or similar members through which pulling ropes *n* may be drawn, which ropes may be tarred ones, or the like and which ropes are provided at their ends with shackles *s* and serve for drawing the tilt tightly down upon the provender, etc., and for fastening it securely in place.

There are four such ropes which extend forth from the lateral parts *b*, as shown in Fig. 1. These ropes are so long that they can form laces, as shown in the lowermost part

of Fig. 2. These portions of the ropes are drawn through the rings *r* of the straps *c*, as well as through similar rings *r²* provided at the longitudinal members of the underframe of the carriage. The ends of the ropes on the same side of the tilt are finally connected with one another by shackles *s* (Figs. 1 and 2).

The corners of the projecting portions *k* of the middle or main part of the tilt are provided with rings or loops *r¹* (Fig. 1). The ropes *n* are first passed through these rings or loops when the tilt has been brought into its position of use upon the provender or the like (position as in Fig. 2) so as to hold said portions *k* in proper position, and only thereafter they are put alternately through the rings *r* and *r²* in order to form lacing, as in Fig. 2.

The middle part *a* is longer than the side parts *b b*. The length of these latter corresponds to the normal length of the wagon (Fig. 2) and the projecting ends *k* of the middle part correspond to the normal height of the goods on the wagon so that the frontal faces of the goods can be securely protected from rain and snow.

The middle part *a* of the tilt projects at its rims *y* over the adjacent rims of the lateral parts *b b*. When the tilt has been brought into its position of use, as in Fig. 2, and when then the ropes *n* are drawn first through the rings *r¹*, and then through the rings *r*, there are formed between said rims oblong apertures *d* which act as ventilation apertures in that air can find access through them to the goods, i. e., to the rough provender or other vegetable.

Removing the tilt from the goods, and rolling or coiling it up can be effected very easily and conveniently (after the frontal portions *k* have been disconnected from the adjacent ends of the side parts *b*) by first throwing the lateral parts *b* upwardly and down upon the middle part *a* so that the three parts lie over one another, and by then rolling or coiling up the superposed parts from both ends towards the center of the tilt or tilt fabric. When the tilt has been rolled or coiled up, cords or straps are wound

around it in order to prevent it from unrolling or uncoiling so that the collapsed tilt keeps its proper shape.

A particular feature of the improved tilt 5 is that it can be used in a twofold way, viz. also as a tent in which case the tilt or, may be, two or more tilts is, or are, employed in connection with different wagons or with poles and struts and similar rigid supporting members not shown, by way of example, in Fig. 3 in which the tent or the barrack consists of two tilts of the type in question. With tilts of the normal size one thereof will form a tent of about 3 x 10 m. bottom size, two 10 combined tents will form a tent of about 100 m.² bottom size, and three combined tilts will form a tent of about 170 m.² It is obvious that also barracks can be erected in this way.

20 I claim:

1. A wagon tilt, comprising, in combination, a longitudinal middle part; two separate longitudinal side parts, straps extending transversely over said three parts on the inner surface thereof and being connected with them, substantially as set forth.

2. A wagon tilt, comprising, in combination, a longitudinal middle part; two separate longitudinal side parts, straps extending transversely over said three parts on the inner surface thereof and being connected with them and rigid fastening means, attached to the ends of said straps, substantially as set forth.

3. A wagon tilt, comprising in combination, a longitudinal middle part, two separate longitudinal side parts which are shorter than said middle part so that end portions of this latter project over the ends of said side parts; straps extending transversely over said three parts on the inner surface thereof and being connected with them, substantially as set forth.

4. A wagon tilt, comprising in combination, a longitudinal middle part, two separate longitudinal side parts which are shorter than said middle part so that end portions of this latter project over the ends of said side parts, the length of these latter parts corresponding to the normal length of the freight wagon and the middle part being longer by as much as corresponds to the normal height of the goods upon the wagon; straps extending transversely over said three parts on the inner surface thereof and being connected with them, substantially as set forth.

5. A wagon tilt, comprising, in combination, a longitudinal middle part, two separate longitudinal side parts extending at their inner edges below the edges of said middle part; straps extending transversely over said three parts on the inner surface thereof and being connected with them, substantially as set forth.

6. A wagon tilt, comprising, in combina-

tion, a longitudinal middle part; two separate longitudinal side parts which are shorter than said middle so that this extends beyond the side parts at both its ends, the length of these ends corresponding to the breadth of 70 said side parts; straps extending transversely over said three parts on the inner surface thereof and being connected with them; means adapted to support the middle part in a raised position in which its end parts and 75 one of its side parts hang vertically and the other side part is adapted to be extended obliquely upwards, for cooperation with a complementary part of another tilt to form a tent.

In testimony whereof I affix my signature.

CHARLES HOFRICHTER.
